ILLUMINATION.

1,346,172.

Specification of Letters Patent. Patented July 13, 1920.

Application filed January 2, 1917. Serial No. 140,173.

To all whom it may concern:

Be it known that we, LUCIAN W. BUGBEE and EDGAR D. TILLYER, citizens of the United States, residing at Southbridge, in 5 the county of Worcester and State of Massachusetts, have invented certain new and useful Improvements in Illumination, of which the following is a specification.

Our invention relates to illumination and 10 has particular reference to that type of sources of illumination disclosed and claimed in our copending application Serial No. 133,635.

One of the leading objects of the present 15 invention is the provision of an improved source of illumination such as a light bulb of the general character described in the application referred to, but which shall make use in addition to the usually employed element of an additional or supplemental 20 source of light radiation.

A further object of the present invention 25 is the provision of an improved bulb in which the reflected heat rays shall be employed to produce luminosity in a substance having a lower point of incandescence than that of the filament and in which consequently the same amount of illumination 30 may be obtained with a less degree of heating of the bulb.

A further object of the present invention 35 is the provision of an improved bulb or source of illumination in which a main conducting filament may be employed for the purpose of giving off both the heat and light radiations, and in which a supplemental filament or medium may be employed which shall give off light radiations under the influence of the heat radiations generated by 40 the conducting filament, but which need not in itself be a conducting substance or in any way coupled with the source of electrical energy.

Other objects and advantages of our improved construction should be readily apparent by reference to the following specification taken in connection with the accompanying drawings, and it will be understood that we may make any modifications in the

specific disclosures illustrated and described 50 within the scope of the appended claims without departing from or exceeding the spirit of our invention.

Figure I represents a vertical sectional view illustrating one embodiment of our im- 55 proved light.

Fig. II represents a similar view of another construction thereof.

Fig. III represents a horizontal sectional view. 60

In the drawings, the numeral 1 designates the base or attaching portion of a bulb provided with the spherical or pear shaped glazed or translucent portion 2 of usual construction, but provided on its inner face 65 with the metallic film or coating 3 having the property of selective reflection of infra red or heat rays and having in addition if desired the property of selective absorption or reflection of the chemical or ultra violet 70 rays, while being transmissive of the light in the visible spectrum.

Inclosed within the bulb is the electrical 75 resistant element or filament 4 of any desired usual construction, either in the form of an upstanding loop as illustrated in Fig. I, or in the form of a double or multiple annular disposed spirals, as indicated in Figs. II and III, the main desideratum in either case being that the center of the arc or curve 80 of the filament or filaments 4 be substantially the same as the center of curvature of the bulb or inclosing member 2.

The purpose of this should be readily apparent, since it will be seen if these parts 85 are concentrically arranged that direct radiating rays from the filament as a source of luminosity impinging upon the reflecting film 3 will, so far as the infra red or heat rays are concerned, be reflected back toward 90 the center of the bulb and at the same time in the direction of the filament, tending to increase the heat in the filament and thus its efficiency. In addition, however, we have shown as secured centrally within the filament, as by the cage 5, which also serves as a support for the filament, the radiant substance 6 adapted to be acted upon by the 95

heat rays. It will be understood that a number of substances may be employed for this purpose, such as a cerium oxid or thorium oxid, and that this substance may 5 be a discontinuous radiator which does not have to be a conductor, in that no electrical current is passed through the substance 6, the heating effect on this substance being entirely from the direct inward radiation 10 from the filament or filaments 4 and the reflected heat radiation stopped off and reflected back to the center by the film 3.

These backwardly reflected radiations will thus increase the temperature of the material 6 until it becomes luminous and gives off heat and light radiations of its own, in this event the heat radiations being again reflected back onto the substance to increase its heating while the light radiations pass 20 through the reflecting film 3 and are useful as visible light.

From the foregoing description taken in connection with the accompanying drawings, the construction and operation of our improvement 25 proved luminous source should be readily apparent, and it will be seen that by the use of our improvement we are able with a relatively small amount of initial energy to produce an extremely desirable and satisfactory light, in that the heat radiations ordinarily forming a large part of the energy consumed in producing illumination in place of being radiated and lost are all reflected back and made use of, while in addition by the provision of the material 6 on which these radiations are focused a much brighter and more satisfactory source of illumination is obtained than is possible even in our previous improvement in which 40 these radiations are focused back on and serve to additionally increase the luminosity of the film itself.

It will also be understood that by the use of our improvement we are able to 45 greatly prolong the life of the bulb in that the heat radiations are not primarily in this instance focused on the filament tending to impair the life of the conductor, but are focused on the inert non-conducting material 50 and consequently in nowise interfere with the conductor.

It will further be understood that while we have especially illustrated and described our invention as applicable in connection 55 with a conducting radiant and a supplemental non-conducting radiant, that it is equally applicable in those cases where the supplemental radiant is also a conductor, or is of a material which will be rendered conductive when suitably heated. In this latter event the reflected radiations impinging upon the supplemental radiant will be condensed or focused by the reflected medium and will serve to raise the temperature of 60 the supplemental radiant to a point where

it will become conductive where additional electrical or other energization may be employed to produce incandescence or luminosity in the supplemental radiant. In this event if the position of the parts is such as 70 is illustrated in the accompanying drawing, the supplemental radiant will be found to be at the focal center of the reflector, consequently all heat radiations therefrom will be focused back thereonto to constantly increase the heating of the supplemental radiant for a given amount of energy and thus increase its luminous efficiency.

It will further be understood that while we have shown our improvement as especially applied to an inclosed bulb, that it is capable of use with various sources of illumination, in connection with which a condensing reflector may be employed, and that we, therefore, do not wish to be limited in any manner to the specific construction here illustrated, which has merely been chosen as satisfactorily disclosing the several generic principles of our invention as combined in the most efficient manner so far determined by us for their utilization for general illumination purposes, it being understood that for specific conditions different specific forms of illuminating devices are advantageously employed, and that our invention is capable of employment in a multiplicity of detailed specific embodiments.

Similarly, it will be understood that it is not necessary for the supplemental retainer 100 to be inclosed by the main radiant or that said parts be concentrically arranged, since the only essential for the carrying out of our invention is that the relationship of the main radiant reflector and supplemental radiant be such that heat radiations emanating from the main radiant and impinging upon the reflecting medium will be reflected or condensed by said reflecting medium onto the supplemental radiant to there produce 110 the desired result.

We claim:

1. A source of luminosity comprising a spherical bulb having a supplemental radiant disposed at the center of the sphere, 115 said bulb having the property of transmission of visible radiations and of reflection of heat radiations, and a main radiant for supplying said radiations encircling the supplemental radiant whereby outwardly 120 directed heat radiations therefrom will be focused back to the supplemental radiant by the inclosing bulb and inwardly directed heat radiations will have a direct heating action on the supplemental radiant, substantially as and for the purpose described.

2. A source of luminosity, comprising a skeleton source of radiant energy, a supplemental radiant disposed within the skeleton source, and a spherical bulb inclosing 130

the radiants, said bulb being concentric with the main and supplemental radiants and having its inner face coated with a metallic film which will transmit visible radiations and retard by reflection and focus back the heat radiations onto the main and supplemental radiants.

In testimony whereof we affix our signatures in the presence of two witnesses.

LUCIAN W. BUGBEE.
EDGAR D. TILLYER.
